CONTAINER

Samuel Platt, San Francisco, Calif.

Application September 27, 1940, Serial No. 358,609

4 Claims. (Cl. 229—87)

This invention relates to containers or boxes as used generally in stores for neckties, handkerchiefs, stockings, scarfs, etc., that are classified as gift items.

The principal object of the invention is an improved container that is economical to make, neat in appearance, and which container is more compact and more easily folded to closed condition than heretofore.

Another object is an improved container that is less susceptible to damage during folding to closed condition, and which container is folded and secured in folded condition without danger of injury to the nails or fingers of the clerk or person folding the same.

Other objects and advantages will appear in the description and drawing annexed hereto.

In the drawing, Fig. 1 is a plan view of a blank of cardboard for folding to form my container.

Fig. 2 is a perspective view illustrating the final step of closing the container formed from the blank of Fig. 1.

Fig. 3 is an enlarged end edge view of the folded container.

As a general rule, where efficient store management is desired, the use of attractive boxes or containers is encouraged over the use of ordinary paper or paper bags, since the customers are more favorably impressed, and the goods purchased are protected against wrinkles, and other injury. The use of cardboard containers for gift items, such as neckties, handkerchiefs, stockings, etc., that are relatively light and readily fold to flat condition, is particularly desirable, since the sender is particularly anxious for the container in which the gift is enclosed to present an attractive appearance, and the recipient is favorably impressed with the store from which the gift is sent.

Heretofore, flat containers for use in containing flat folded items, have been of the type closure flaps that fold over the bottom or one main side of the container forming the top or other main side thereof. One of the flaps was formed with the conventional slot for receiving the tab on the other flap, thus locking the flaps together. The clerks in stores are reluctant to use these containers, particularly during the busy hours of the day, since the locking of the flaps is awkward and difficult and frequently the tabs or slots are torn, involving loss of time in repacking the gift items, and the operation of locking the flaps closed frequently causes injuries to the cuticles and nails of the fingers due to the difficulty of quickly effecting the interlock between the tabs. Also these conventional containers have narrow edge walls perpendicular to the main walls, thus making the packages more bulky than required, and necessitating additional folding operations.

My improved structure eliminates the above objections and thus effects a material saving in time in packaging goods, the result being that the clerks that wrap the goods that are sold, will use the containers without injury to themselves or to the containers, and by so doing, effect a material saving of time over older methods.

In detail, Fig. 1 represents a substantially rectangular blank formed of cardboard or the like, which blank is formed with a generally central folding crease 1, substantially dividing the container into a rectangular bottom, or main side 2, and a top side 3. Along the edge of bottom 2 that is opposite the top 3 is an extension 4, the juncture between said extension 4 and bottom 2 being defined by a crease 5 that is parallel with crease 1. Along the two remaining opposite edges of bottom 2 are end extensions 6, and the junctures between extension 6 and bottom 2 are defined by parallel creases 7 extending perpendicularly of creases 1, 5, and extending between corresponding ends of said creases 1, 5. The extension 4 and extensions 6 are relatively narrow with respect to the bottom 2, and constitute strips of the material of the blank extending longitudinally of the edges along which they are disposed. Extensions 6 are preferably wider than extension 4, for a reason later to be described.

Centrally between the ends of extension 4 is a tab 8, which tab is rectangular in shape and elongated longitudinally of extension 4. This tab projects from the free longitudinally extending edge of the extension 4 and its length is approximately one-third of the length of the extension, although this may be varied somewhat, according to circumstances, such as the size of the container, the goods to be packed, etc. However, in any event the tab should preferably be of appreciable length.

The free edge of the top 3 that is parallel with crease 1 is formed with an outwardly opening rectangular recess 9 the depth of which in direction perpendicularly of said free edge, is substantially the width of the tab 8. The length of recess 9 is substantially the length of tab 8, being very slightly greater, however, for a reason later to be explained. This recess 9 is centrally between the remaining opposite free edges of top 3 that extend perpendicularly of creases 1, said opposite free edges of top 3, being in longitudinal continuation of creases 7. Midway between the end edges of recess 9, and along the long edge of said recess, said latter edge is formed with a shallow thumb receiving recess 10, the edge of said latter recess being curved with its concave side facing into the main recess 9.

From the foregoing explanation, it will be seen that tabs 11 are formed at opposite ends of recess 9, which tabs substantially correspond in length (longitudinally parallel with creases 1, 5), to the

areas defined on two sides by the end edges of tab 8 and the edges of extension 4 that extend oppositely outwardly of said end edges.

In operation the operator lays the blank of Fig. 1 flat on the counter or table, and positions the handkerchief or stockings, or tie, or any other relatively flat item or items, on the bottom 2. The flaps 6 are then folded over the end margins of bottom 2 and over the portions of the items on said bottom that may extend to creases 7. After this, the extension 4, carrying tab 8, is folded over the ends of flaps 6 that are adjacent thereto, and which extension and tab may overlap the items on bottom 2. The operator then folds over the top 3, which will completely extend over the flaps 6 and the items on bottom 2. The top 3 when so folded, is locked in position covering the items on said bottom by grasping the said top between the thumb and fingers of the hand 12 (Fig. 2), the fingers being along the outer side of the blank at crease 1, and the thumb being in the thumb recess 10. The top 3 is then bowed outwardly, relative to bottom 2, by the hand and tabs 11 are slipped below the opposite end portions 4' of extension 4, which end portions extend outwardly of the tab 8, while the tab 8 extends between opposite end edges of recess 9 and below the finger notch 10. Upon releasing the pressure of the fingers that causes bowing of top 3, the top 3 will straighten out appreciably, toward a flat position, and tabs 11 will slide on flaps 6 to a position under the end portions 4' of extension 4, while tab 8 will lie below the margin of recess 9 along which the finger notch 10 is formed. The box will now be held closed against accidental opening, and the operator may tie the conventional ribbon or other binder about the same, or the purchaser may prefer to carry the same without further wrapping, in the same manner as a lady's flat purse. The flaps 6 thus function to provide a support for sliding of the top 3 to locked or closed position, and to open the box, it is only necessary to bow the top 3, as indicated in Fig. 2, until the flaps 11 clear the end portions 4' of extension 4.

The use of the term "bottom" and "top" is made to identify the two main sides of the container, since these are substantially the only sides on the container, the other sides being mere edges along creases 1, 5 and 7. It will be manifest, of course, that the extension 4 cooperates with top 3 to overlie the bottom 2.

The locking of top 3 closed along one edge of the container, rather than in the center, is essential to effect a sufficiently secure closing of the container, since the extension 4 is relatively narrow with respect to the top 3, and will not have the resiliency transversely thereof that is required to effect a release of the top 3 without actually distorting the top 3 to a bowed condition. Each of the tabs 8 and 11, being about equal to each other in length, and extending in longitudinal alignment along the margin along crease 5, effects a very effective means of securing the top closed.

The width of the tab 8, and of end portions 4' and the depth of slot 9, in direction transversely of the longest dimensions thereof, may be varied according to the requirements of the user about the proportion shown in the drawings, which is adequate to provide a container adapted to enclose fairly large articles or a plurality of smaller ones, since the top will bow out sufficiently to accommodate such article or articles without separation of the alternate tabs. It is highly important, however, in any case, that the material of

the blank be sufficiently resilient to tend at all times to straighten out so that the tabs on the extension 4 and the tabs on top 3 will respectively remain in engagement with the respective margins of top 3 and extension 4 adjacent thereto.

Having described my invention, I claim:

1. A relatively flat container comprising opposed, substantially rectangular top and bottom walls of similar size formed from a single semi-rigid, relatively resilient, elongated sheet of cardboard having a transverse folding crease and folded on itself along said crease, said folding crease defining one of the corresponding adjacent edges of said walls; an elongated flap integral with said bottom wall extending lengthwise thereof along the edge of the bottom wall that is opposite said crease; a second folding crease formed in said sheet at the juncture of said flap and said bottom wall and commonly defining one edge of said bottom wall and flap; a tab integral with said flap projecting outwardly of the edge of said flap opposite said second folding crease; said flap being folded along said second crease over the marginal portion of said bottom wall adjacent said second folding crease; a pair of spaced tabs integral with said top wall positioned between said flap and said marginal portion of said bottom wall; the said tab on said flap being positioned between said top wall and said bottom wall when said flap and said top wall are folded over the same side of said bottom wall, and the outer free edges of said pair of tabs being substantially in engagement with the juncture between said flap and said bottom wall when said flap and said top wall are so folded.

2. In a construction as defined in claim 1, a pair of flaps on said bottom wall integral therewith and respectively extending from the edges thereof that are at right angles to said second folding crease; said pair of flaps being folded over said bottom wall to positions respectively between the tabs of said pair and said bottom wall.

3. A substantially rectangular container comprising opposed, rectangular top and bottom walls of similar size formed from a single sheet of relatively resilient, semi-rigid sheet material integrally joined along one of corresponding edges of said top and bottom wall; a folding crease in said sheet at said integrally connected edges to facilitate swinging said top and bottom walls relatively at said crease; a relatively narrow flap integral with said bottom wall extending along the edge of the latter opposite said folding crease; a second crease extending along the juncture between said flap and said bottom wall for folding said flap over the marginal portion of the top wall that extends along said flap when said top wall is in opposed relation to said bottom wall; said second crease being along a line commonly defining one edge of said flap and one edge of said bottom wall; a tab integral with said flap projecting outwardly of the free edge thereof, that is opposite said second crease and a recess formed in said marginal portion of said top wall and opening outwardly of the free edge thereof positioned to slidably pass said tab therethrough to below said top wall when said flap is folded over said marginal portion, whereby said flap and said tab will secure said top wall in closed position.

4. In a construction as defined in claim 3, said first mentioned crease being along a line commonly defining one edge of said top wall and one edge of said bottom wall.
